(57) **CLAIM**

The ornamental design for an electrical receptacle housing, as shown and described.

DESCRIPTION

FIG. 1 is a perspective view of an electrical receptacle housing according to the invention, taken from its top, front and right side;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, taken from its top, rear and left side; and,

FIG. 9 is a perspective view thereof, taken from its bottom, rear and right side.

The broken lines illustrate portions of the electrical receptacle housing that form no part of the claimed design.
